UNITED STATES PATENT OFFICE

JOHN C. KORTH, OF MAPLEWOOD, NEW JERSEY

DESIGN FOR AN OIL BURNER

Application filed April 2, 1930. Serial No. 35,133. Term of patent 14 years.

To all whom it may concern:

Be it known that I, JOHN C. KORTH, a citizen of the United States, residing at Maplewood, in the county of Essex and State of New Jersey, have invented a new, original, and ornamental Design for Oil Burners, of which the following is a specification, reference being had to the accompanying drawing, forming a part thereof.

The figure is a perspective view of an oil burner, showing my new design, the dotted lines indicating the motor, head and control box.

I claim:

The ornamental design for an oil burner, as shown and described.

JOHN C. KORTH.
